(57) **CLAIM**

The ornamental design for a solar panel, as shown and described.

DESCRIPTION

FIG. 1 is a front, top, and right side perspective view of a first embodiment of a solar panel;

FIG. 2 is a top plan view thereof, the bottom plan view being a mirror image of the top plan view shown;

FIG. 3 is a front elevational view thereof, the rear elevational view forms no part of the claimed design;

FIG. 4 is a left side elevational view thereof, the right side elevational view being a mirror image of the left side elevational view shown;

FIG. 5 is a detail view along line 5-5 in FIG. 3 of the overlapping cells thereof;

FIG. 6 is a front, top, and right side perspective view of a second embodiment of a solar panel;

FIG. 7 is a top plan view thereof, the bottom plan view being a mirror image of the top plan view shown;

FIG. 8 is a front elevational view thereof, the rear elevational view forms no part of the claimed design;

FIG. 9 is a left side elevational view thereof, the right side elevational view being a mirror image of the left side elevational view shown; and,

FIG. 10 is a detail view along line 10-10 in FIG. 8 of the overlapping cells thereof.

The broken lines in the drawings illustrate subject matter that forms no part of the claimed design.
